UNITED STATES PATENT OFFICE.

THOMAS A. DAVIES, OF NEW YORK, N. Y.

FISH-PLATE FOR RAILROAD-RAIL JOINTS.

SPECIFICATION forming part of Letters Patent No. 320,641, dated June 23, 1885.

Application filed April 22, 1885. (No model.)

To all whom it may concern:

Be it known that I, THOMAS A. DAVIES, of the city, county, and State of New York, have invented a new and useful Improvement 5 in Fish-Plates for Railroad-Rail Joints, of which the following is a full, clear, and exact description.

Reference is to be had to the accompanying drawings, forming a part of this specification, 10 in which similar letters of reference indicate corresponding parts in both the figures.

Figure 1 is a sectional end elevation of a pair of my improved fish-plates, a rail to which they are applied, the spring-washer, 15 and a nut, a bolt being shown in side elevation. Fig. 2 is a sectional plan view of the same, one pair of bolts being shown with nuts and the other pair without nuts.

The object of this invention is to provide 20 fish-plates constructed in such a manner that the rails forming joints will be held rigidly in line both horizontally and laterally, and will thus serve as continuous rails.

The invention consists in fish-plates constructed with a flange upon their inner sides, 25 near their upper edges, and in the combination of such fish-plates with the rails, the spring-washers, and the bolts and nuts of the track, as will be hereinafter fully described, 30 and then claimed.

A B represent two adjacent rails of a railroad-track forming a joint. C are the fish-plates, the side edges of which are beveled to fit against the beveled lower sides of the 35 heads and the beveled upper sides of the base flanges of the rails A B. The fish-plates C are made of such a breadth that their side edges will come to their seats against the heads and base-flanges of the rails before the 40 inner sides of the said fish-plates come in contact with the webs of the said rails.

Upon the inner sides of the fish-plates C, near their upper edges, are formed flanges D, which rest against the webs of the rails A B, 45 as shown in Fig. 1.

In applying my improved fish-plates to the rails the upper edges of the fish-plates C are placed against the lower sides of the heads of

the rails A B, with the flanges D resting against the webs of the rails, and the lower 50 parts of the fish-plates are then forced inward to their seats upon the base-flange of the rails, so that the said fish-plates will always have three substantial bearings upon the rails, the first and second against the heads and 55 base-flanges of the rails, to hold the said rails rigidly in a horizontal line, and the third against the webs of the rails, to hold the said rails rigidly from lateral movement.

The fish-plates C D are secured in place by 60 the ordinary bolts and nuts E F, and my improved angular spring-washers G, for which Letters Patent have been allowed. With this construction the tendency of the spring-washers G will always be to feed the fish-plates to 65 their bearings, so that any wear that may occur will be at once taken up and the joints kept rigid.

The nuts F are locked in place when screwed home by breaking down the screw-threads of 70 the bolts and nuts, or either of them, at the outer side of the said nuts, as indicated at the point H in Fig. 1, so that it will be impossible for the said nuts to work loose.

Having thus described my invention, I 75 claim as new and desire to secure by Letters Patent—

1. A fish-plate, C, made, substantially as herein shown and described, with a flange, D, upon its inner side near its upper edge, 80 whereby the said fish-plate will always adjust itself to three distinct bearings, as set forth.

2. The combination, with the rails A B, and the fish-plates C, fitting between the heads and base-flanges of the rails, and having flanges 85 D along their inner sides, near their upper edges, resting against the webs of the rails, of the angular spring-washers G, and the bolts and nuts E F, substantially as herein shown and described, whereby the ends of the rails 90 will be held rigidly from vertical and lateral movement, as set forth.

THOS. A. DAVIES.
